UNITED STATES PATENT OFFICE.

GEORGE B. BOSCO, OF CHICAGO, ILLINOIS.

FORM CLAMP.

Application filed April 11, 1921. Serial No. 460,355.

To all whom it may concern:

Be it known that I, GEORGE B. Bosco, a citizen of the United States of America, and a resident of Chicago, county of Cook, and 5 State of Illinois, have invented certain new and useful Improvements in Form Clamps, of which the following is a specification.

This invention relates to form clamps particularly designed for holding together 10 the separable parts of a concrete mold such as those which are used in building concrete columns, joists and girders.

The main objects of this invention are to provide a form clamp which is simple, inexpensive and effective, and having an improved form and arrangement of interlocking parts; to provide improved means for adjusting the parts to accommodate different sizes of molds; and to provide a detachable 15 tool for drawing the interlocking parts toward each other to tighten the clamp.

An illustrative embodiment of this invention is shown in the accompanying drawings, wherein—

25 Figure 1 is a perspective view of the form clamp applied to a column mold which is shown partly broken away.

Fig. 2 is a side elevation, partly in section, of the clamp and tool showing the interfitting parts of the clamp in interlocking relation.

Fig. 3 is a fragmentary side elevation, partly in section, showing the detachable tool in its open position.

35 Fig. 4 is a plan of the interlocking members.

The majority of form clamps which are now in use comprise a plurality of similarly formed sections having means for adjustment at each corner of the clamp. Such clamps cannot properly be applied to a column mold without the services of two men because the clamp sections should be interlocked simultaneously on opposite sides of 45 the mold in order to prevent the form from being distorted.

The present clamp comprises a single flexible band having adjustably secured thereto a pair of members formed for interlocking 50 engagement for securing the band around the form. The interlocking members are drawn together into locking position by a separate tool which is detachable so that one such tool may serve a large number of 55 clamps.

Referring to the drawings, the clamp is shown applied to a concrete column mold comprising side sections which are formed of planks 1 secured together by battens 2 arranged on the outside of the mold at certain intervals and disposed transversely to the planks.

In the form shown, the clamp comprises a flexible element 3, adapted to embrace the mold and having its ends secured to interlocking members 4 and 5 arranged for telescopic engagement, and which are drawn into interfitting relation by a detachable tool 6.

The flexible element preferably comprises 70 a flat strap of metal, such as spring steel, of sufficient width to insure a proper grip on the interlocking members.

Extending through one end of each of the interfitting members, is a pair of transversely disposed slots 7, arranged in spaced relation to receive the metal strap. The ends of the strap are laced through the slots 7 in the manner shown in Fig. 2, so as to be secured against slipping by the friction of 80 the overlapping parts. This form of lacing permits the interfitting members to grip the flexible strap at any point along its length, and the clamp is therefore adjustable to accommodate molds of various sizes.

The member 5 is in the form of a flat slide having formed at its outer end a pair of oppositely disposed lugs 8. The member 4 is bifurcated to form a guideway 9 for receiving the slide 5. Formed at the other end of 90 the member 4, is a pair of oppositely disposed lugs 10 arranged adjacent the slots 7. The lugs 8 and 10 are arranged to be engaged by the tool 6 for drawing the interfitting members into position to permit their being interlocked. Extending through the members 4 and 5 is a plurality of apertures 11, arranged to receive a locking pin 12, and disposed so as to permit the interlocking of the parts in various relative positions. The locking pin is preferably in the form of a nail which may be driven into the batten of the mold.

The detachable tool comprises a lever arm 13 having arranged at one end thereof oppositely disposed claws 14 and 15 which are pivotally mounted on pins 16 and 17 respectively. The axes of the pivot pins are spaced apart, so that the claws are drawn inwardly toward each other by the movement of the 110

lever arm in one direction with either one or both of the pivot pins serving as a fulcrum for the lever.

In operation, the clamp is applied to a column mold with the flexible strap embracing the battens 2, as shown in Figure 1, any appreciable slack in the strap having first been taken up by adjusting the lacing. The tool 6 is then applied to the members 4 and 5 with the claws engaging the lugs 8 and 10. By operating the lever arm, the strap is tightened by drawing the interfitting members into position to permit the insertion of the pin 12 through certain of the aligned apertures. When the locking pin has been inserted through the apertures and driven into the mold, the detachable tool may be removed and used on other clamps.

When the clamp is used on a circular form, suitable filler blocks, (not shown) may be inserted between the interlocking members and the mold.

It is apparent from the foregoing description that the present invention provides a simple and effective column clamp in which there are no projecting parts and which can be readily applied to a mold by one person.

Although but one specific embodiment of this invention has been herein shown and described it will be understood that numerous details of the construction shown may be altered or omitted without departing from the spirit of this invention as defined by the following claims.

I claim:

1. A form clamp comprising a flexible element adapted to embrace the form and having a pair of members mounted thereon, said members being formed for telescopic engagement and having apertures for receiving a locking pin, and a detachable tool for drawing said members into position to per-

mit the insertion of said pin into certain of said apertures.

2. A form clamp comprising a flexible element adapted to embrace the form and having a pair of members adjustably mounted thereon, said members being formed for telescopic engagement and having apertures for receiving a locking pin, and a detachable tool for drawing said members into position to permit the insertion of said pin into certain of said apertures.

3. A form clamp comprising a flexible element adapted to embrace the form, a pair of members on said element formed for interfitting engagement, and a detachable tool for drawing said members into interfitting engagement to permit the interlocking of said members, said tool comprising a lever arm having a pair of oppositely disposed claws pivotally mounted thereon with the axes of their pivots spaced apart whereby either of said pivots is adapted to serve as the fulcrum of said lever.

4. A form clamp comprising a flexible metal strap adapted to embrace the form and having a pair of members adjustably mounted thereon, said members being formed for telescopic engagement and having apertures arranged to receive a locking pin, lugs formed on said members, and a detachable tool formed to engage said lugs for drawing said members into position to permit the insertion of said pin into certain of said apertures, said tool comprising a lever arm having a pair of oppositely disposed claws pivotally mounted thereon with the axes of their pivots spaced apart whereby either of said pivots is adapted to serve as the fulcrum of said lever.

Signed at Chicago this 9 day of April, 1921.

GEORGE B. BOSCO.
